AUTOMATIC ADJUSTABLE RAIL BRACE

Arthur R. Schulze, Johnstown, Pa., assignor to
Carnegie-Illinois Steel Corporation, a corpora-
tion of New Jersey

Application February 3, 1948, Serial No. 5,920

6 Claims. (Cl. 238—292)

1
This invention relates to an automatic adjustable rail brace and more particularly to such a brace which is used in conjunction with means for holding down the rail.

In adjustable rail braces most commonly used at present, the locking means are either horizontal or vertical threaded bolts and/or cotter pins. Adjustment requires loosening or removing the nuts from the bolts or removing the cotter pins. The bolts are frequently corroded with the nuts seized on the bolts. Loosening or removal then causes damages which requires the replacement of either the nut or the nut and bolt. Cotter pins must necessarily be replaced. An adjustable rail brace is one in which means are provided for maintaining the brace in tight engagement with the rail as wear and corrosion of the parts occur.

It is an object of my invention to provide a rail brace which is automatically adjustable.

Another object is to provide an adjustable brace which does not require bolts or cotter pins for locking the brace in position.

These and other objects will be more apparent after referring to the following specification and attached drawings, in which:

Figure 1 is a plan view of my invention;

Figure 2 is a sectional view taken on the line II—II of Figure 1;

Figure 3 is a sectional view taken on the line III—III of Figure 1;

Figure 4 is a view, partly in section, showing the wedge in retracted position;

Figure 5 is a view similar to Figure 4 showing the wedge in a forward position; and

Figure 6 is a sectional view taken on the line VI—VI of Figure 4.

Referring more particularly to the drawings, the reference numeral 2 indicates a tie plate which is provided with a seat 4 for the rail 6. Spaced from the rail, at one side thereof, is a longitudinal stop 8 which is welded or otherwise fastened to tie plate 2. An adjustable brace 10 has one end contacting the head of the rail as shown and the other end resting on the plate 2 and extending toward the stop 8. It will be understood that the brace 10 could be provided with side flanges that extend down to the rail base. It will also be understood that shouldered non-clamping bolts applied in a well known conventional manner, vertically up through the tie plates, may be used instead of the inverted "U" 36 and the spring clamp 40 in order to position the adjustable brace laterally but allowing automatic forward movement toward the rail as

2
looseness of the brace may permit. The web 12 of the brace has an opening 14 therein for a purpose which will appear later. The stop 8 is arranged at an angle to the rail 6 so that a space 16 is provided between the bottom of the brace 10 and the stop 8, the space being wider at one end than at the other. A wedge 18 is provided to fit in this space. The stop 8 instead of having a vertical contact face, as shown, against the wedge 18 may be tapered downwardly away from the wedge 18 with a corresponding contact surface on the wedge, thus preventing any accidental vertical displacement of the wedge. Another alternative would be to provide an overhanging rib on stop 8. A longitudinal opening 20 extends substantially throughout the length of the wedge. At the narrow end of the wedge, a hole 22 extends from the outside of the wedge and communicates with the opening 20 so that a shoulder 24 is provided, the hole being considerably smaller in cross-section than the opening 20. The brace 10 is provided with a lug 26 which extends into alignment with the opening 20 as best shown in Figures 4 and 5. The end 28 of this lug 26 serves as a transverse abutment against which bears a spring cone 30. A spring 34 in the opening 20 extends from abutment 24 to the spring cone 30.

Fastened to the tie plate 2 is an inverted U-shaped member 36 which extends upwardly from the tie plate into the opening 14. The length of the inverted U member 36 is substantially as great as the length of the opening 14, but the opening 14 is considerably greater in width than the width of the inverted U 36.

The stop 8 has a slot 38 at its upper inner corner. A spring clip 40, shaped as shown in Figure 2, passes through the opening in the inverted U member 36 with one end bearing on the base of the rail 6 and the other end being bent downwardly into the slot 38.

The device is assembled and functions as follows:

A bolt 42 is passed through the hole 22, the coil spring 34, and is threaded into the spring cone 30 with the bolt head bearing against the forward end of the wedge so that the spring is compressed, as shown in Figures 1 and 6. The adjustable brace 10 is placed over the inverted U member 36 in position against the rail 6 and the wedge 18 is placed loosely between the brace 10 and stop 8. The bolt 42 is then removed permitting the spring 34 to expand between the spring cone 30 and the abutment 24, urging the wedge 18 longitudinally of the rail toward the narrow

end of the space 16, as shown in Figure 5. This movement of the wedge forces the rail brace 10 against the rail since the rail brace cannot move longitudinally because of the contact of the inverted U 36 with the end of the opening 14. Transverse movement of the brace 10 is permitted, however, by virtue of the greater width of the opening 14. The spring clip 40 is then inserted into the opening of the inverted U 36 into the position shown in Figure 2. This prevents disassembly of the unit in an upward direction and at the same time holds the rail 6 in the groove 4.

When a train passes over the rail 6, vibrations occur and during this time the spring 34 will force the wedge 18 longitudinally in the direction of the narrow width thereof, thus automatically adjusting the rail brace.

In disassembling the device, the bolt 42 is inserted through the hole 22 and threaded into the spring cone 30 so that the spring is compressed between the cone 30 and the shoulder 24. The spring clip 40 is then pried loose with a pinch bar and the wedge 18 is raised, also by the pinch bar.

While one embodiment of my invention has been shown and described, it will be apparent that other adaptations and modifications may be made without departing from the scope of the following claims.

I claim:

1. An automatic adjustable rail bracing device comprising a tie plate having a seat portion for the base of the rail, a stop member fastened to the tie plate and spaced from said rail, an adjustable brace bearing against the rail and extending in the direction of the stop member from the rail to the tie plate, said brace having an opening therein intermediate its ends, an inverted U member fastened to said tie plate and extending upwardly through said opening, the length of the inverted U member being slightly less than the length of said opening and the width of the inverted U member being substantially less than the width of said opening, said stop member and brace being separated to provide a space therebetween which is wider at one end than at the other, a wedge in said space bearing against said stop member and against said brace to hold the brace against said rail, a transverse abutment on said wedge adjacent the narrow end, a transverse abutment on said brace extending into said space adjacent the wide end thereof, a spring bearing against both of said abutments to urge the wedge longitudinally in the direction of its narrow end, and a spring clip extending through the inverted U-member with one end bearing on the base of the rail and the other end bearing on the stop member.

2. An automatic adjustable rail bracing device comprising a tie plate having a seat portion for the base of the rail, a stop member fastened to the tie plate and spaced from said rail, an adjustable brace bearing against the rail and extending in the direction of the stop member from the rail to the tie plate, said brace having an opening therein intermediate its ends, an inverted U member fastened to said tie plate and extending upwardly through said opening, the length of the inverted U member being slightly less than the length of said opening and the width of the inverted U member being substantially less than the width of said opening, said stop member and brace being separated to provide a space therebetween which is wider at one end than at the

other, a wedge in said space bearing against said stop member and against said brace to hold the brace against said rail, said wedge having a longitudinal hole therethrough, a longitudinal opening of greater cross-section than said longitudinal hole communicating with said hole, a transverse shoulder at the end of said longitudinal opening adjacent the narrow end, a transverse abutment on said brace extending into said space adjacent the wide end thereof, a spring in said longitudinal opening bearing against said transverse shoulder and the transverse abutment of said brace to urge the wedge longitudinally in the direction of its narrow end, and a spring clip which extends through the inverted U member with one end bearing on the base of the rail and the other end bearing on the stop member.

3. An automatic adjustable rail bracing device comprising a tie plate having a seat portion for the base of the rail, a stop member fastened to the tie plate and spaced from said rail, an adjustable brace bearing against the rail and extending in the direction of the stop member from the rail to the tie plate, said brace having an opening therein intermediate its ends, an inverted U member fastened to said tie plate and extending upwardly through said opening, the length of the inverted U member being slightly less than the length of said opening and the width of the inverted U member being substantially less than the width of said opening, said stop member and brace being separated to provide a space therebetween which is wider at one end than at the other, a wedge in said space bearing against said stop member and against said brace to hold the brace against said rail, said wedge having a longitudinal hole therethrough, a longitudinal opening of greater cross-section than said longitudinal hole communicating with said hole, a transverse abutment at the end of said longitudinal opening adjacent the narrow end, a transverse abutment on said brace extending into said space adjacent the wide end thereof, a spring cone in said longitudinal opening abutting the transverse abutment on said brace, a spring bearing against the wedge abutment and said cone to urge the wedge longitudinally in the direction of its narrow end, and a spring clip which extends through the inverted U member with one end bearing on the base of the rail and the other end bearing on the stop member.

4. An automatic adjustable rail bracing device comprising a tie plate having a seat portion for the base of the rail, a stop member fastened to the tie plate and spaced from said rail, an adjustable brace bearing against the rail and extending in the direction of the stop member from the rail toward the tie plate, means for limiting longitudinal movement of the brace, means for limiting vertical movement of the brace, said stop member and brace being separated to provide a space therebetween which is wider at one end than at the other, a wedge in said space bearing against said stop member and against said brace to hold the brace against said rail, said wedge having a longitudinal downwardly facing opening therein terminating in a transverse abutment adjacent the narrow end, a relatively stationary transverse abutment in said space adjacent the wide end thereof, and a spring in said longitudinal opening bearing against both of said abutments to urge the wedge longitudinally in the direction of its narrow end, and hold down means for holding said rail and wedge on said tie plate.

5. An automatic adjustable rail bracing device

comprising a tie plate having a seat portion for the base of the rail, a stop member fastened to the tie plate and spaced from said rail, an adjustable brace bearing against the rail and extending in the direction of the stop member from the rail toward the tie plate, means for limiting longitudinal movement of the brace, means for limiting vertical movement of the brace, said stop member and brace being separated to provide a space therebetween which is wider at one end than at the other, a wedge in said space bearing against said stop member and against said brace to hold the brace against said rail, said wedge having a longitudinal hole therethrough, a longitudinal downwardly facing opening of greater cross-section than said longitudinal hole communicating with said hole, a transverse abutment at the end of said longitudinal opening adjacent the narrow end, a transverse abutment on said brace extending into said space adjacent the wide end thereof, and a spring in said longitudinal opening bearing against both of said abutments to urge the wedge longitudinally in the direction of its narrow end, and hold down means for holding said rail and wedge on said tie plate.

6. An automatic adjustable rail bracing device comprising a tie plate having a seat portion for the base of the rail, a stop member fastened to the tie plate and spaced from said rail, an adjustable brace bearing against the rail and extending in the direction of the stop member from

the rail toward the tie plate, means for limiting longitudinal movement of the brace, means for limiting vertical movement of the brace, said stop member and brace being separated to provide a space therebetween which is wider at one end than at the other, a wedge in said space bearing against said stop member and against said brace to hold the brace against said rail, said wedge having a longitudinal hole therethrough, a longitudinal downwardly facing opening of greater cross-section than said longitudinal hole communicating with said hole, a transverse abutment at the end of said longitudinal opening adjacent the narrow end, a transverse abutment on said brace extending into said space adjacent the wide end thereof, a spring cone in said longitudinal opening abutting the transverse abutment on said brace, and a spring bearing against the wedge longitudinally in the direction of its narrow end, and hold down means for holding said rail and wedge on said tie plate.
